(57) **CLAIM**

We claim the ornamental design for a bicycle component, as shown and described.

DESCRIPTION

FIG. 1 is a perspective view of a bicycle component embodying our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left-side elevation view thereof; and,

FIG. 7 is a right-side elevation view thereof.

The broken lines in the drawings illustrate portions of the bicycle component that form no part of the claimed design. In the drawings, the dot-dash lines represent boundaries of the claim and form no part of the claimed design.
